UNITED STATES PATENT OFFICE.

GEORGE E. MARLATT, OF PASADENA, CALIFORNIA.

TYPOGRAPHICAL MACHINE.

1,389,369.

Specification of Letters Patent.

Patented Aug. 30, 1921.

Application filed March 17, 1921. Serial No. 452,964.

To all whom it may concern:

Be it known that I, GEORGE E. MARLATT, a citizen of the United States, residing at Pasadena, in the county of Los Angeles and

5 State of California, have invented new and useful Improvements in Typographical Machines, of which the following is a specification.

My invention relates to the matrix-distributing elements of typographical machines of the linotype class in which matrices are withdrawn from a storage magazine, assembled in line for casting a type-slug therefrom and subsequently returned 10 to the magazine through the instrumentality of the distributor with which this invention is concerned. This present invention has for its principal objects to provide for a more rapid distribution of the matrices to 15 the channels of the magazine and to provide improved means for quickly and automatically stopping and disconnecting the distributor-driving elements following certain abnormal occurrences.

25 Certain matrices, such, for example, as spaces, leaders and dashes, are often employed in such quantity and with such frequency that a shortage thereof results pending their return to the magazine; also, many 30 linotype machines are provided with several magazines each containing a different kind or size of matrices and designed for rapid substitution one for another to meet the requirements of the work in hand. It is 35 therefore desirable that the distributor be cleared as rapidly as possible of matrices belonging in any one of such magazines so that another magazine may be substituted therefor. It will be apparent that any increase in the speed with which the matrices 40 are carried to their individual magazine channels will tend to lessen or eliminate the annoying delays explained above.

In the accompanying drawings which are 45 to be read in connection with this specification, Figure 1 is a rear elevation, with the center portion broken away, of the matrix-distributer system of a linotype machine, showing my invention in relation thereto; 50 Fig. 2 is an end view of the gear system at the right of Fig. 1; Fig. 3 is a section on a line 3—3 through the gear system shown in Fig. 2; Fig. 4 is a plan view of part of the clutch shown at the left of Fig. 55 1; Fig. 5 is a vertical section on the line 5—5 of Fig. 1; Fig. 6 is a vertical section

on the line 6—6 of Fig. 1; Fig. 7 is a vertical section on the line 7—7 of Fig. 1, and also shows certain parts numbered 41 to 48 not elsewhere shown.

Similar numerals refer to similar parts throughout the several views.

The common practice has been to employ a set of three distributor screws for carrying the matrices from the distributor box 1 65 to their individual channels. The speed at which these screws may be rotated has been limited by the fact that sufficient time must be allowed for a matrix to drop entirely into the magazine entrance-channels 2 before the 70 next following matrix carried by the screws reaches the point at which such matrix has dropped; otherwise a dropping matrix would interfere with a following matrix remaining in engagement with the screws. 75 This present invention involves retaining distributor screws similar to those in common use and doubling their speed for rapid distribution of the matrices, and doubling the distance between the matrices when engaged by the screws in order to avoid the interference between a dropping and a traveling matrix which would otherwise ensue as a result of the increased speed.

Heretofore the cam 3 which controls the 85 lifting of the matrices 5 into engagement with the carrier screws has been fixed on the upper rear screw 4, effecting the lifting of a matrix at each rotation of the screws. This invention provides for rotating the cam 90 3 at half the speed of the screws so as to lift a matrix at each alternate rotation of the screws and to thus double the distance between the traveling matrices. With the speed of the screws doubled, the matrices 95 will be cleared from the distributor box 1 at the usual speed and will then be carried at double the usual speed and with double the usual distance between them when in engagement with the screws.

The reduction of the speed of the cam 3 relative to the screw 4 is attained as follows: A driving gear 6 is fixed on the screw 4 and turns a gear 7 at reduced speed proportionate to its larger size; the larger gear 105 7 is integral with a second small gear 8 which turns a second larger gear 9 integral with the cam 3, thus completing the reduction of speed to half that of the screw 4 on which the gear 9 and cam 3 are 110 loosely mounted. The intermediate gears are mounted on a shaft 10 carried by the

bracket 11 in which the screw 4 is hung from a shaft 12 in the usual manner. The screw 4 is capable of being swung outwardly and upwardly and the several gears and cam 3 are carried therewith without disturbing their inter-relation. The cam 3 may occupy its usual position on the screw 4 to coöperate with the roller 13 on the matrix-lift lever 14, thus rendering my invention readily applicable to outstanding machines.

In addition to the advantages already set forth incident to an increased speed of the distributor screws, such increase also permits a freer and more direct drop of the matrices 5 from the distributor bar 16 into the magazine entrance channels 2. Heretofore the speed of the distributor screws has been such that the upper (front) lug 15 of the matrices would strike the thread 17 of the lower screw when dropping into the channels. This difficulty is overcome to an extent by providing a guard strip over the lower screw, but this guard is also objectionable for the reason that it likewise interferes with a direct drop of the matrices, throwing them backward against the channel entrance plate 18 with sufficient force to interfere with their travel through the entrance channels and into the magazine 19. With the increased speed of the screws herein provided for, the upper matrix-ear will pass between the spirals of the thread on the lower screw, the advancing thread serving as a guide instead of an obstruction to the matrix and rendering the objectionable screw guard unnecessary.

The increased speed of the screws may be attained by increasing the size of the usual driving gear 20, or by changing the relative size of the driving pulley (not shown) and the driven pulley 21, or by a combination of both methods.

Causes other than those above stated occasionally interfere with the travel of the matrices through the entrance channels. For example, a bent matrix or an unclean channel in the magazine may cause the matrices to clog the entrance channels. In any such case the matrices accumulate in the channels until they interfere with the matrices being carried along by the distributor screws. It has been the common practice to provide for automatically stopping the screws in such occurrences by permitting the partitions 22 to bend at their upper ends against the advance of the thread of the lower screw, the bending partitions in turn acting upon and through other devices to separate members of the clutch which drives the screws. Such an arrangement has proven objectionable for the reason that the repeated flexing of the partitions tends to leave them permanently bent, with the result that the matrices drop on their upper edges instead of between them as intended. With

such an arrangement, the clutch must be of sufficient strength to bend the partitions and therefore considerably stronger than is necessary to drive the screws under normal conditions.

In this invention I provide for automatically stopping the distributor screw without bending the partitions, and for reducing the strength of the clutch to the minimum necessary to rotate the screws under normal conditions.

With these objects in view I provide the usual clutch pulley 21 with a cam formed on its hub. Shoulders 23 on the cam engage rollers 24 carried by the clutch arms 25. These clutch arms are mounted on and turn with the shaft 26 which carries the drive gear 20. This gear 20 meshes with the gears 27 and 27' on the ends of the front upper and lower distributor screws. The arrangement of the drive gear 20 and the several gears on the distributor screws does not differ from the usual arrangement of these parts, except that the gear on the shaft 26 may be enlarged as hereinbefore stated. The pulley 21 is loosely mounted on the shaft 26 to turn therewith under normal conditions and thereon under abnormal conditions. The shaft 26 has a flattened portion 28 carrying a pin 29 which serves as a pivot for the clutch arms 25. The inner ends of the clutch arms have bifurcations 30 which co-operate with the pivot pin 29 to keep the arms in engagement with the shaft. Springs 31 secured to pins 32 in the outer ends of the clutch arms serve to keep the rollers 24 in engagement with the shoulders 23 on the cam. In the event of undue resistance to the rotation of the distributor screws because of any of the conditions hereinbefore described, such resistance will hinder the rotation of the shaft 26 but will not prevent the pulley 21 from continuing to rotate. The shoulders 23 on the cam will therefore force the rollers 24 outward, tilting the clutch arms and carrying the springs 31 across the center 29 on which the arms are pivoted, thus disengaging the rotating pulley 21 from the shaft 26 which is geared to the distributor screws.

Shafts 33 on which the rollers 24 are mounted project from the clutch arms and, when the arms are tilted as described, the outer ends of these shafts rest upon a member 34 slidably mounted in the bearing 35 and are held in engagement therewith by the clutch springs with sufficient tension to prevent any creeping of the shaft 26 due to the friction of the continuously-rotating pulley. With the parts in the position and relation just described, and the abnormal condition causing the separation of the clutch members having been remedied, the clutch is restored by manually moving a rod 36 extending across the distributor within convenient

reach of the attendant. This rod is bent downwardly at its outer end, passes through a recess 37 in the bearing 35 which supports the slidable member 34 and shaft 26, and engages the slidable member 34 as shown. Movement of the rod 36 to the right will cause the conical end of the slidable member 34 to raise the outer ends of the shafts 33 and thus tilt the clutch arms and restore the parts to normal relation for rotating the distributor screws. A spring 38 serves to restore the operating rod 36 and the member 34. In the event that the rollers 24 strike upon instead of between the shoulders 23 at the instant the clutch is restored, the arms 25 are lifted by such contact away from their pivot pin 29 but are immediately restored by action of the clutch springs when the rollers become properly seated between or against the shoulders 23 of the cam.

In addition to the engaging means between the clutch arms 25 and shaft 26 already described, arms 39 on the shaft 26 serve a similar purpose and spurs 40 on the shaft 26 also engage the clutch arms when in normal operative position.

The entrance channel 41 as a unit is capable of being moved away from the distributor screws for the purpose of removing the matrices from a clogged channel or for other purposes. It is supported for such movement on a pivot 42 in the frame 43 which supports the distributor. It is essential that the opening of the entrance channel shall automatically stop the distributor screws; otherwise, if an attendant should inadvertently open the entrance while matrices were being carried by the distributor screws, the matrices in dropping would be scattered at large instead of entering their channels. To stop the rotation of the screws in such cases I provide a pawl 44 which is normally held out of engagement with the teeth of the driving gear 20 by reason of its contact with an arm 45 extending from the entrance channel 41. When the entrance is opened its initial movement will permit the pawl 44, urged by a spring 48, to engage one of the teeth of the gear 20 and the clutch members will therefore be disconnected in the manner before described. When the entrance is entirely opened as shown in broken lines in Fig. 7 a projection 46 on the entrance channel will contact with an arm 47 of the pawl lever and disengage the pawl from the gear, thus permitting the distributor screws to be rotated manually by means of a knob 49 on the shaft 26 or otherwise, for any purpose, prior to the restoration of the clutch by means of the rod 36 as before described.

While distributor screws of the usual number, diameter, pitch, and speed, have been used as a basis of explanation in the foregoing description, it is to be understood that they have been used for such purpose only.

For example, if screws of smaller pitch than those commonly employed, with a corresponding increase in speed, should prove desirable in order to more rapidly clear the matrices from the distributor box; or if a fourth screw be added to guide the matrices when traveling or dropping, any such arrangement is to be considered as coming within the spirit and purpose of this invention.

Having fully described my invention, what I claim as new and desire to secure by Letters Patent, is:

1. In a typographical machine, in combination, the matrix-distributor screws, a matrix-lifting member for lifting the matrices into engagement with said screws, a cam for controlling the action of said matrix-lifting member, and means for effecting such relative speed between said distributor screws and said cam as will cause a matrix to be engaged by said screws at alternate rotations of the screws.

2. In a typographical machine, in combination, matrices having upper and lower lugs on opposite edges thereof, upper and lower distributor screws for engaging said lugs and thus propelling said matrices to points of distribution, speed-control means for rotating said screws at such speed as will cause the upper lugs of said matrices to clear and pass midway between successive spirals of the thread on the lower of said screws when said matrices drop at their points of distribution, reciprocating matrix-lift means for lifting the matrices one at a time and at each reciprocation thereof into engagement with said screws and speed control means for said matrix-lift means whereby a matrix will be lifted only at each alternate rotation of said screws.

3. In a typographical machine, in combination, a distributor box, rotating distributor screws, matrices capable of being lifted one at a time from said distributor box to said screws, a reciprocating lift element for lifting one of said matrices into engagement with the distributor screws at each reciprocation of said lift element, and means independent of said matrices for causing said lift element to reciprocate only at each alternate rotation of said distributor screws.

4. In a typographical machine, in combination, the distributor box for receiving and clearing matrices, magazine entrance channels, distributor screws for carrying matrices from said distributor box to said entrance channels, matrices capable of being placed in engagement with said screws, a reciprocating lift element for lifting said matrices from said distributor box and into engagement with said screws, and means independent of said matrices for causing said screws to rotate twice to each reciprocation of said lift element.

5. In a typographical machine, in combination, matrix-distributing screws capable of being resisted to hinder their rotation, a driving shaft geared to said screws, a pulley mounted on said shaft and capable of revolving either therewith or thereon, clutch arms mounted on said driving shaft and normally engaging said pulley, cam means on said pulley for disengaging said clutch arms therefrom when the distributor screws are resisted, resilient means for holding said clutch arms in engagement with said pulley in the absence of resistance to said screws and out of engagement therewith in the event of such resistance, and manually operable means extending parallel with said distributor screws for reengaging said clutch arms with said pulley following their disengagement therefrom.
- 10 6. In a typographical machine, in combination, the matrix-distributer screws, the driving shaft for said screws, the gears connecting said shaft with said screws, a clutch having self-contained and self-sufficient means for separating the driven element from the driving element thereof when resistance is offered to said screws or to said driving shaft, the distributor entrance channel capable of being moved toward and away from said screws, a pawl 44 capable of offering resistance to said driving shaft for causing the separation of the clutch elements in the absence of resistance to the distributor screws when the distributor entrance channel is moved partly away from said screws, means 46 for disengaging said pawl from said driving shaft when and while the distributor entrance channel is moved and remains further away from said screws, and other means 45 for holding said pawl out of engagement with said driving shaft when and while the distributor entrance channel is restored to normal position toward said screws.
- 15 7. A combination as specified in claim 6, embodying also clutch-restoring means of a character employing the cone 34 under control of the operating rod 36 and the restoring spring 38.
- 20 8. In a typographical machine, in combination, the distributor screws subject to resistance by an abnormal condition or occur-
- 25 rence, a clutch for driving said screws and having self-contained and self-sufficient means for disengaging the driven element from the driving element thereof when resistance to said screws is communicated to said clutch, the cone 34 for restoring said clutch, the rod 36 for operating said cone, and the spring 38 for restoring said rod and cone.
- 30 9. In a typographical machine, in combination, the distributor box, matrices therein, distributor screws for conveying matrices from the distributor box to points of distribution, the reciprocating lift element for lifting a matrix from the distributor box to the distributor screws at each reciprocation of said lift element and at each alternate rotation of said screws, a clutch for driving said screws, and self-contained, self-sufficient and independent means directly associated with and composing said clutch but capable of disconnecting the driving element of the clutch from the screws in the event of undue resistance to the distributor screws.
- 35 10. A combination as specified in claim 9, embodying also the clutch restoring means recited in claim 7.
- 40 11. In a typographical machine, a distributor and a clutch for driving said distributor, said clutch embodying driving and driven elements so constructed and interrelated that the features thereof which serve normally to render said clutch operative will under abnormal conditions also serve to render said clutch inoperative independent of any outside construction or influence other than the abnormal condition temporarily prevailing, said clutch embodying no construction for rendering it inoperative which is not also required for rendering it operative.
- 45 12. A combination as specified in claim 11, embodying also the clutch restoring means recited in claim 7.
- 50 In testimony whereof I hereunto set my hand this 12th day of March, 1921, in the presence of two attesting witnesses.
